OSCILLATION GENERATOR

John F. Farrington, Flushing, N. Y., assignor to
Hazeltine Corporation, a corporation of Delaware

Application May 17, 1937, Serial No. 143,075

6 Claims. (Cl. 250—36)

This invention relates to oscillation generators and, particularly, to generators of oscillations of periodically varying frequencies.

Generators of this type are especially useful in apparatus designed for recording acoustic phenomena, as, for example, the recording of acoustic performance of sound-reproducing systems. In one well-known method of obtaining such recordings, electrical oscillations at audible frequencies are generated and impressed upon the sound-producing apparatus to be tested and the resulting sound waves are propagated through a testing chamber to a suitably located sound pick-up device, or microphone, connected to a recording apparatus. In certain types of chambers, for example, rooms with "hard" walls, floors, and ceilings, reflection of the sound waves sets up interference patterns and stationary waves. These interference patterns shift with frequency. Under such conditions, if a microphone or corresponding device of the apparatus is disposed in a fixed position in the chamber, this position may be such that a satisfactory recording is not obtainable. For example, a microphone may be located at a node of a stationary wave of a particular frequency so that it gives no response thereto.

Various solutions of the foregoing problem have heretofore been suggested, but they have not been completely satisfactory. In certain cases the microphone has been continuously moved about the fixed position to integrate the sound energy. In accordance with a more satisfactory solution, however, the generator has been designed to develop audio-frequency oscillations normally at the desired pre-determined frequency, but cyclically deviating about this frequency, so that the undesirable effects mentioned above are avoided and a satisfactory recording of the sound wave of the average frequency propagated, ordinarily the predetermined frequency, is obtained. For this purpose it is essential that the deviations of the sound waves from each predetermined audio frequency be approximately the same percentage of such predetermined frequency, for all frequencies of the audible range within the range of the generator. In conventional generators of this type, two high-frequency oscillations are generated and mixed in a modulator to develop the predetermined audio- or beat-frequency signal. The frequency of one of the high-frequency oscillations is adjusted to provide the required adjustment of the audio-frequency signal over the range, while the frequency of the other is cyclically varied to produce the

desired deviations in the audio-frequency signal. The audio-frequency deviations in kilocycles, therefore, tend to be constant over the tuning range of the generator rather than a constant percentage of any selected audio frequency, which latter is the desired relationship. Heretofore, this desired frequency deviation has been obtained approximately by means of relatively complicated switching arrangements, whereby the effectiveness of the means employed for causing these deviations has been adjusted in steps, providing different actual deviations for different component portions of the audio-frequency range. Such arrangements, however, have required repeated and relatively complicated adjustments and, moreover, have provided a control of the range of deviation only roughly approximating that required.

It is an object, therefore, of the present invention to provide an improved oscillation generator for generating oscillations normally at a predetermined frequency, but cyclically deviating about such frequency and including means whereby the range of the deviations may be readily adjusted.

A further object of the invention is to provide an improved oscillation generator, embodying high-frequency oscillation generating means of the character described and an additional tunable high-frequency oscillation generating means, for generating beat-frequency oscillations at any predetermined frequency within a wide range but cyclically deviating thereabout.

A still further object of the invention is to provide an oscillation generator of the character last described, wherein cyclically deviating high-frequency oscillation generating means is automatically controlled in accordance with the tuning of the other high-frequency oscillation generating means, so that the range of deviations of the beat-frequency oscillations is adjusted closely to approximate the same percentage of the beat frequency for all beat frequencies within the range of the generator.

In accordance with the present invention, there is provided an oscillation generator including an oscillation circuit for normally developing oscillations at a predetermined frequency. The generator also comprises means including an auxiliary cyclically-tunable circuit coupled to the oscillation circuit to shift the resonant frequency thereof, thereby to effect cyclical deviations of the oscillations from the predetermined frequency. There is further provided means for adjusting the coupling between the circuits to adjust

the range of deviations without affecting the said predetermined frequency.

In one satisfactory embodiment of the invention, the oscillation generator comprises a first 5 high-frequency oscillation generating means which is tunable over a predetermined range and a second high-frequency oscillation generating means normally developing oscillations at a fixed predetermined frequency, and means are coupled 10 to these two generating means for deriving therefrom beat-frequency oscillations. Auxiliary means are associated with the second oscillation generating means for effecting cyclic deviations from the predetermined frequency produced by 15 it. Control means are arranged to adjust the effectiveness of the auxiliary means, thereby to adjust the range of the deviations. Unicontrol means are so connected as simultaneously to tune the first generating means and to adjust the control 20 means at unequal rates and in a predetermined relation, thereby to adjust the range of the deviations substantially directly in accordance with the frequency of the first generating means as it is tuned over its tuning range.

25 For a better understanding of the invention, together with other and further objects thereof, reference is had to the following description taken in connection with the accompanying drawing and its scope will be pointed out in the appended 30 claims.

In the accompanying drawing, Fig. 1 is a circuit diagram of a complete oscillation generator embodying the present invention; Figs. 2 and 3 are graphs representing certain operating characteristics of the generator of Fig. 1 to aid in the understanding of the invention; Fig. 4 is a side view, partially schematic, of uncontrolled tuning and variable inductance elements suitable for use in connection with the invention; and Fig. 5 40 is an end view of the variable inductance element of Fig. 4.

Referring now more particularly to Fig. 1 of the drawing, there is shown schematically a beat-frequency oscillation generator embodying the 45 present invention in a preferred form. In general, this generator includes a tunable high-frequency generator indicated generally at 10 and a fixed-tuned high-frequency generator indicated generally at 11. High-frequency buffer amplifiers 50 12 and 13 are connected to the output circuits of the generators 10 and 11, respectively, and the output circuits of these amplifiers are, in turn, connected to a common input circuit of a modulator 14. The output circuit of the modulator 55 may be connected through a beat-frequency amplifier 15 to a sound-producing device or other utilization apparatus 16.

The high-frequency generators 10 and 11 are, in general, similar in construction and operation 60 and corresponding elements thereof are designated on the drawing by similar reference numerals. The generator 10 comprises an oscillation circuit 17 and a vacuum-tube oscillator 18. The circuit 17 includes an inductance winding 19 in 65 parallel with an adjustable condenser 20. Series condensers 21 and 22 and series condensers 23 and 24 are connected across the oscillation circuit, as shown. Condensers 21, 22, 23, and 24 provide the main tuning capacitance for the circuit 70 17, while adjustable condenser 20 provides the capacitance required to change the frequency of the circuit over a narrow range to vary the beat frequency over a wide range. The grid-cathode circuit of tube 18 is connected across the 75 condenser 22, a leak resistor 25 being connected

between the grid of this tube and ground. The anode circuit of the tube 18 includes a feed-back winding 26 inductively coupled to the winding 19. Operating voltage is supplied to the anode of the tube from a suitable source, indicated at +B, by 5 way of a resistor 27 and the winding 26. A suitable high-frequency by-pass condenser 28 is provided to return the alternating plate current to the cathode. The input circuit of the high-frequency amplifier 12 is connected across condenser 10 24, as shown.

The high-frequency generator 11 being, as stated above, of the same general construction as the generator 10, a detailed description of the parts thereof which are similar to parts of the generator 10 is unnecessary. For the purpose of clarity, the oscillation circuit of the generator 11 has been designated 17a. The circuit 17a is not tunable so the condenser 20a, which corresponds to the adjustable condenser 20 of the circuit 17, 20 is a fixed padding condenser adjustable only for aligning the circuit 17a with the circuit 17 when the condenser 20 is at its minimum value. Further, in the circuit 17a there is provided a composite inductance element, corresponding to the winding 19 of the circuit 17, which includes the winding 19a and an auxiliary winding 19b. The generators 10 and 11 are preferably shielded, as indicated by the broken lines.

The system as thus far described is substantially conventional and its operation being well understood in the art, a detailed explanation thereof is unnecessary herein. Briefly, however, oscillations are generated by the generator 11 at a fixed predetermined high frequency and by the 35 tunable generator 10 at a different predetermined high frequency, preferably below the fixed frequency. These oscillations are then amplified in the amplifiers 12 and 13, which serve as buffer stages, and mixed in conventional manner in the modulator 14 to develop beat-frequency or audio-frequency oscillations. The beat- or audio-frequency oscillations are then amplified in the 40 amplifier 15 and translated to the reproducer 16 or other corresponding device for conversion into sound or other use.

Referring now more particularly to the portion of the system embodying the present invention, there is provided in connection with the oscillation circuit 17a an auxiliary tunable circuit 30 50 comprising inductance windings 31 and 32, a resistor 33, and capacitance elements including the main frequency-determining condenser 35, which is adjustably fixed, and a relatively small adjustable tuning condenser 34. A suitable motor 37 is 55 operably connected to the shaft of the condenser 34 for continuously adjusting the rotor of this condenser, thereby cyclically to vary the resonant frequency of the circuit 30 about its normal predetermined frequency, which is that of the circuit 60 17a.

The winding 31 of circuit 30 is inductively coupled to the winding 19b and arranged to provide therewith a variacoupler, indicated generally at 36, adjustable to vary the coupling between the 65 circuits 30 and 17a. Variacoupler 36 is preferably shielded from the other parts of the system, as indicated by the broken lines.

Unicontrol means, indicated by the broken line 70 38, are connected to the tuning condenser 20 of 70 the oscillation circuit 17 and to the variacoupler 36 for simultaneously adjusting these elements, thereby to adjust the coupling between the auxiliary circuit 30 and the oscillation circuit 17a in accordance with the frequency to which the os- 75

cillation circuit 17 is tuned. Preferably an indicator 39 and a dial 40 are provided in connection with the unicontrol means, the dial being calibrated, for example, 0-10,000 cycles, corresponding to the beat or audio frequencies developed by the system for various settings of the unicontrol means which adjusts the tuning condenser 20.

In the assembly of the system, the oscillation circuit 17 is preferably initially adjusted to develop its maximum frequency, for example, 120 kilocycles, the tuning condenser 20 providing its minimum capacitance and the indicator 39 being at 0 on the dial 40. With the variocoupler 36 adjusted to provide substantially zero coupling between the circuits 30 and 17a, the circuit 17a is adjusted to have the same resonant frequency as the oscillation circuit 17 by adjusting condenser 20a. Obviously, with both of the high-frequency generators 10 and 11 developing oscillations at the same frequency no beat- or audio-frequency oscillation is developed by the modulator 14 and the output of the system is zero. The circuit 30 is next so adjusted that, with its tuning condenser 34 at its intermediate or mean position, it is resonant at the same frequency as the circuit 17a. The maximum coupling provided by variocoupler 36 is limited to such a value that, under this condition, the circuit 30 has no effect on the resonant frequency of the circuit 17a. Under certain conditions the circuit 30 reflects or introduces reactance into the circuit 17a and thereby shifts the resonant frequency thereof. The amount of reactance so introduced depends mainly upon two factors: (1) the difference between the resonant frequency of the circuit 30 and that of the circuit 17a, as controlled by adjustment of the condenser 34, and (2) the amount of coupling between these circuits, as controlled by the adjustment of the variocoupler 36.

In the operation of the system, the motor 37 rotates the shaft and the rotor of the condenser 34 and thereby causes cyclic deviations of the resonant frequency of the circuit 30 above and below its normal value, which is also that of the circuit 17a. With any appreciable coupling between the circuits, reactance is introduced into the circuit 17a from the circuit 30 during these deviations, thereby causing corresponding deviations of the resonant frequency of the circuit 17a.

The range of the deviations in frequency of circuit 17a depends upon the coupling between the circuits 17a and 30, and this range may be controlled by adjusting the variocoupler 36.

Adjustments of the condenser 34 providing the frequency deviation of the circuit 30 with respect to its mean resonant frequency effect corresponding frequency deviation of the circuit 17a, but these deviations are substantially linear with respect to the condenser adjustment only within predetermined limits. More particularly, this relationship holds only so long as the series reactance of the circuit 30, at the resonant frequency of the circuit 17a, is less than its resistance. The adjustment of the condenser 34 upon the tuning of circuit 30, therefore, preferably is so restricted that the series reactance of this circuit at the resonant frequency of the circuit 17a is always substantially less than its resistance, or well within the limits providing the linear relationship. In the preferred arrangement, the circuit constants are such that the ratio of reactance of the inductance elements to the resistance of the circuit 30 is relatively high at the resonant frequency of this circuit.

In order to obtain satisfactory results in the

use of the system in acoustic testing, it is essential that the deviation of the beat- or audio-frequency signal developed be approximately the same percentage of its average frequency for all frequencies within the audible range of the system. A desirable deviation of the audio-frequency oscillations has been found to be $\pm 5\%$ of the normal or predetermined frequency plus some constant low frequency of the order of 5 or 10 cycles. The additional constant component of the frequency deviations is effective to break up the standing wave sound patterns at very low beat frequencies, such as from 30 to 100 cycles, at which a 5% deviation alone would not be sufficient. At the high-frequency end of the range, however, for example, at 10 kilocycles, the 5% deviation is sufficient, while the additional 5 or 10 cycle deviation is inappreciable.

Since the deviations of the audio frequencies are caused by frequency deviations of the oscillations developed by the generator 11, the extent of these deviations in cycles is independent of the tuning of generator 10 to vary the beat-note frequency. In order, therefore, to obtain the approximately uniform percentage deviation of the beat frequency over the entire tuning range of the generator, there are provided unicontrol adjusting means 38 for the condenser 20 and the variocoupler, as described above. The unicontrol means 38 serves so to adjust the variocoupler 36, as the condenser 20 is adjusted over its range, as to increase the coupling between the circuits 17a and 30 and thus increase the beat-frequency deviations as the frequency of the high-frequency generator 10 is decreased to increase the beat-note frequency developed in the modulator 14.

In order that the increase in beat-frequency deviations bear the desired relation to the average or normal frequency of the beat notes, the several elements of the system may be proportioned as follows: For convenience, the rotor plates of the condenser 20 are preferably so shaped that there is a relation between angular displacement and the resonant frequency of the circuit 17 such that the beat frequency between generators 10 and 11 is substantially logarithmically related to the rotational angle of condenser 20. For ideal results, the rate of adjustment of the variocoupler is generally different from that of the adjustment of the tuning condenser 20 and this may, of course, be accomplished in any suitable manner. For example, this may be accomplished by utilizing a reduction gear between the unicontrol elements which operate the condenser 20 and the variocoupler and by including in series with the fixed winding of the variocoupler an auxiliary winding so proportioned and arranged as to effect the required difference in rate of coupling adjustment provided by the variocoupler 36 and capacitance adjustment provided by condenser 20. Such an arrangement is described hereinafter in connection with Figs. 4 and 5.

In order to aid in the explanation of the operation of the system described above, reference is made to Figs. 2 and 3. In Fig. 2 curve A illustrates the relation between the frequencies developed by the generator 10 and the adjustment of the tuning condenser 20. Here the abscissae represent angular displacements of the rotor of the condenser 20 in degrees, and the ordinates represent resonant frequency of the circuit 17 in cycles. Obviously, the resultant beat frequency is the difference between the fixed frequency of the generator 11, for example, 120,000 cycles, and the frequency developed by generator 10, which

ranges between 120,000 to 110,000 cycles. It will be seen from the curve A that a logarithmic variation of the beat frequency is accomplished by the angular adjustment of the condenser rotor, 5 this being due, as stated above, to the shape of the rotor plates.

In Fig. 3 there is shown a characteristic curve B illustrating the performance obtained by the system shown in Fig. 1 with respect to the frequency deviation control. Here the abscissae 10 represent the normal beat frequencies developed by the system and the ordinates represent the total range of frequency deviation, both in cycles. It is clearly shown by the curve B that for a low 15 frequency, for example, 100 cycles, a range of deviation of approximately 20 cycles is obtained, while for a high frequency, for example, 10,000 cycles, a range of deviation of approximately 1,000 cycles is obtained. In other words, a deviation of approximately $\pm 5\%$ of the audio frequency 20 and 10 cycles is obtained over the entire range.

While, in accordance with the present invention, any suitable mechanism, either electrical or 25 mechanical, may be provided as the unicontrol device 38, one example of a mechanical unicontrol arrangement is illustrated in Figs. 4 and 5. According to this arrangement, the winding 19b of the variocouples 36 comprises winding elements 19c and 19d in series, rigidly secured to a fixed arm 41 of a support 42, while the winding 31 is mounted on a movable member 43. A shaft 44 is rotatably mounted in the support 42 and the member 43 is rigidly secured thereto, so that, 35 upon rotation of the shaft, the winding 31 may be adjusted between a position coaxial with the winding 19c providing a maximum coupling and a position, as shown in Fig. 5, with its axis displaced from, but parallel to, the axis of the winding 19d, providing a minimum coupling. 40 The auxiliary winding 19d serves to vary the rate of adjustment of the coupling as the winding 31 is adjusted between its positions of maximum and minimum coupling, that is, it provides an increased amount of coupling at the 45 low-frequency end of the tuning range over that which would be provided by the winding 19c alone and thereby aids in the obtaining of the required rate of coupling variation to give the 50 desired variation in frequency deviation over the tuning range of the generator. The proportions and dimensions of winding 19d are determined empirically to obtain the characteristic illustrated in Fig. 3.

An operating knob 45, having an indicator 39 mounted thereon, is secured to one end of the shaft 44 and a gear 46 is secured to its opposite end. The rotor 20a of the tuning condenser 20 is secured to one end of a shaft 47, having a gear 48a secured to its opposite end in mesh 55 with the gear 46. These gears are so proportioned that rotation of the shaft 44 effects rotation of the shaft 47 and, hence, adjustment of the condenser 20 at a predetermined greater rate 60 than that of the variocoupler, thereby, in co-operation with the shape of the condenser rotor and the variocoupler arrangement described above, providing the desired frequency deviation at different frequencies of the tuning range of 65 the generator, as illustrated in Fig. 3.

While there has been described what is at present considered to be the preferred embodiment of this invention, it will be obvious to those skilled in the art that various changes and 70 modifications may be made therein without de-

parting from the invention, and it is, therefore, aimed in the appended claims to cover all such changes and modifications as fall within the true spirit and scope of the invention.

What is claimed is:

1. An oscillation generator including an oscillation circuit for normally developing oscillations at a predetermined frequency, means including an auxiliary cyclically tunable circuit coupled to said oscillation circuit to shift the resonant frequency thereof, thereby to effect cyclic deviations of said oscillations from said predetermined frequency, and means for adjusting the coupling between said circuits to adjust the range of said deviations without affecting 15 said predetermined frequency.

2. An oscillation generator including an oscillation circuit normally developing oscillations at a predetermined frequency, means including an auxiliary tunable circuit coupled to said oscillation circuit and having a mean resonant frequency equal to said predetermined frequency, 20 means for cyclically tuning said auxiliary circuit to shift the resonant frequency of said oscillation circuit and thereby to effect cyclic deviations of 25 said oscillations from said predetermined frequency over a relatively narrow range, and means for adjusting the coupling between said auxiliary circuit and said oscillation circuit to adjust the range of 30 said deviations without affecting said predetermined frequency.

3. An oscillation generator including an oscillation circuit normally developing oscillations at a predetermined frequency, means including an auxiliary cyclically tunable circuit inductively 35 coupled to said oscillation circuit to shift the resonant frequency thereof, thereby to effect cyclic deviations of said oscillations from said predetermined frequency, and means for adjusting the inductive coupling between said circuits 40 to adjust the range of said deviations.

4. An oscillation generator comprising a first 45 oscillation generating means tunable over a predetermined range, a second oscillation generating means including an oscillation circuit normally developing oscillations at a predetermined frequency, means including an auxiliary cyclically tunable circuit inductively coupled to said oscillation circuit for shifting the resonant frequency thereof, thereby to effect cyclic deviations of said 50 oscillations from said predetermined frequency, control means for adjusting the inductive coupling between said circuits to adjust the range of said deviations, means coupled to said two generating means for deriving therefrom beat-frequency oscillations, and unicontrol means for simultaneously tuning said first generating means and adjusting said control means, thereby to adjust said range of deviations as said first generating means is tuned over its tuning range.

5. An oscillation generator comprising a first 60 oscillation generating means tunable over a predetermined range, a second oscillation generating means including an oscillation circuit normally developing oscillations at a predetermined frequency, means including an auxiliary tunable circuit coupled to said oscillation circuit and having a mean resonant frequency equal to said 65 predetermined frequency, means for cyclically tuning said auxiliary circuit to shift the resonant 70 frequency of said oscillation circuit, thereby to effect cyclic deviations of said oscillations from said predetermined frequency over a relatively narrow range, control means for adjusting the effectiveness of said tuning means and unicon- 75

5 trol means for simultaneously tuning said first generating means and adjusting said control means at unequal rates and in a predetermined relation to adjust said range of deviations substantially directly in accordance with the frequency of said first generating means as it is tuned over its tuning range.

6. An oscillation generator comprising a first oscillation generating means tunable over a predetermined range, a second oscillation generating means for normally developing oscillations at a predetermined frequency, auxiliary means for effecting cyclic deviations of said oscillations from said predetermined frequency, control

means for adjusting the effectiveness of said auxiliary means to adjust the range of said deviations, means coupled to said two generating means for deriving therefrom beat-frequency oscillations, control means for tuning said first generating means, and unicontrol means for simultaneously adjusting said two control means at unequal rates and in a predetermined relation to adjust said range of deviations substantially directly in accordance with the frequency of said beat-frequency oscillations as said first generating means is tuned over its tuning range. 10
